WINDOW BLIND

Stanley Barnett, Mount Vernon, N.Y.
(490 Nepperhan Ave., Yonkers, N.Y. 10701)

Filed Feb. 3, 1970, Ser. No. 21,224

Term of patent 14 years

Int. Cl. D25—02

U.S. Cl. D21—6

Fig. 1

Fig. 2

FIG. 1 is a front elevational view of a window blind showing my new design;

FIG. 2 is a side elevational view thereof, the other side being similar; and

FIG. 3 is a bottom plan view thereof.

I claim:

The ornamental design for a window blind, substantially as shown.
